Primary Examiner — Brett Miller*Assistant Examiner* — Nader Abadir(74) *Attorney, Agent, or Firm* — Jeffrey Pervanas; Riches, McKenzie & Herbert LLP**CLAIM**

We claim the ornamental design for a glass, as shown and described.

DESCRIPTION

FIG. 1 is a side elevational view of a glass showing our new design; with the other side view being identical;
FIG. 2 is a bottom elevational view thereof;
FIG. 3 is a top elevational view thereof;
FIG. 4 is a front top perspective view thereof; and,
FIG. 5 is a front bottom perspective view thereof.
The dash-dash broken lines are directed to environment and are for illustrative purposes only, while the dash-dot broken lines represent the bounds of the claimed design; the broken lines form no part of the claimed design.

1 Claim, 2 Drawing Sheets**Related U.S. Application Data**

No. 29/697,227, filed on Jul. 5, 2019, now abandoned.
